UNITED STATES PATENT OFFICE.

JOSEPH MATHISON, OF BOSTON, MASSACHUSETTS, ASSIGNOR TO ROWEN-MATHISON MACHINERY COMPANY, A CORPORATION OF MAINE.

MACHINE FOR SEWING BUTTONS TO THE UPPERS OF BOOTS OR SHOES.

No. 902,828.

Specification of Letters Patent.

Patented Nov. 3, 1908.

Application filed March 12, 1908. Serial No. 420,657.

To all whom it may concern:

Be it known that I, JOSEPH MATHISON, a citizen of the United States, residing at Boston, in the county of Suffolk and State of Massachusetts, have invented new and useful Improvements in Machines for Sewing Buttons to the Uppers of Boots or Shoes, of which the following is a specification.

This invention relates to machines for sewing shank-eyed buttons to the uppers of boots and shoes and is of that class of such machines in which the button is secured to the upper of a boot or shoe by two loops of the same thread, one of said loops extending 10 through the upper and through the eye of said button, while the other of said loops extends through the first loop and around and beneath the eye of the button, the two loops thus forming a flat knot and being so connected to each other, to the button, and to the upper of the boot or shoe that said button cannot be detached from the upper by any pull to which it may be, in practice, subjected, even though the thread be cut between any two adjacent buttons.

The object of this invention is to provide a machine of the character set forth which shall be simple, durable and rapid and the invention consists in a machine in which the needle passes a primary loop of thread through the upper and the eye of the button, then feeds said button and the upper forward the full distance between the centers of two adjacent buttons while the needle is 30 through the eye of the button, and subsequently performs the remainder of the stitching operation in the manner herein-after set forth. By thus feeding the material and the button the total distance between the centers of the buttons, with the needle extending through the eye of the button which is being fed, and then performing the stitching operation, the buttons are accurately spaced and the eye of the button is 40 drawn down close to the upper, making a very accurate, neat and secure piece of work.

This invention further consists in certain improved means for guiding the button as it is being fed by the needle from the raceway to a spring-pressed button holder, whereby said button is held in position while the loop forming instrumentalities are in operation.

In the machine of this invention the buttons are fed down a raceway and stopped at

the bottom thereof against a suitable stop, from whence said button is removed by the needle which first passes upwardly through the eye of the button and then feeds the button past said stop out of the raceway. It is, therefore, desirable that the center of the eye of the button should be in alinement with the needle when said needle moves upwardly to pass through said eye.

In practice, buttons having different sized heads and different sized eyes are employed. This results in the center of the eyes of different styles of buttons assuming different positions relatively to the needle, and one of the objects of this invention is to provide 65 convenient means for adjusting the needle, so that the same will aline with the center of the eye of the lowermost button in the raceway, independent of the size of the head or the size of the eye of said button. When 70 the space between the centers of buttons is increased or diminished, it becomes necessary to adjust both the needle and the raceway, and it is a further object of this invention to provide convenient means for securing 75 this result, i. e., for simultaneously adjusting the raceway and the needle so as to preserve the alinement of the needle with the eye of the lowermost button in said raceway when the needle is making its upward 80 movement to pass through said eye.

The invention finally consists in the combination and arrangement of parts set forth in the following specification and particularly pointed out in the claims thereof.

Referring to the drawings: Figure 1 is a front elevation of my improved button sewing machine. Fig. 2 is a left hand side elevation of the same. Fig. 3 is a rear elevation of the same. Fig. 4 is a plan view 90 of the same. Fig. 5 is a detail section, partly in elevation, taken on line A—A, Fig. 3, illustrating a portion of the mechanism by means of which a reciprocatory motion is imparted to the needle and needle bar. Fig. 100 6 is a further detail of the mechanism illustrated in Fig. 5 and is a section, partly in elevation, taken on line B—B, Fig. 1. Fig. 7 is a detail side elevation of the mechanism for imparting a reciprocatory movement to the needle and needle bar, with one of the rock-shafts shown in section. Fig. 8 is a sectional elevation taken on line C—C of Fig. 1, illustrating the mechanism by means of which a rocking movement is im- 110

parted to the needle and needle bar, and mechanism to impart a rocking movement to the raceway and button hopper. Fig. 9 is a detail section, partly in elevation, taken 5 on line D—D of Fig. 8. Fig. 10 is a left hand side elevation, in detail, of the presser foot mechanism, a portion of the frame and the driving shaft and rock-shafts being shown in section. Fig. 11 is a sectional plan 10 taken on line E—E of Fig. 1, illustrating the thread clamping mechanism. Fig. 12 is a left hand side elevation, partly in section, on line F—F, Fig. 3, further illustrating the thread clamping mechanism. Fig. 13 is a detail left hand side elevation 15 of the take-up mechanism, the frame and driving shaft being shown in section. Fig. 14 is a perspective view of the primary hook and the mechanism whereby a rocking and lateral reciprocating movement may be imparted thereto, this view being taken in 20 the direction of the arrow *a*, Fig. 4. Fig. 15 is a detail side elevation of the secondary hook and the mechanism by means of which 25 said hook is rocked. Fig. 16 is a perspective view of the button ejector and the spring-pressed holder for the button, as viewed in the direction of the arrow *a*, Fig. 4. Fig. 17 is a detail section, partly 30 in elevation, taken on line G—G, Fig. 2, illustrating the button pusher, the button holder and the work-rest. Fig. 18 is a detail side elevation of the brush rocking mechanism, the shaft being shown in section. Fig. 19 is a perspective view, as viewed in 35 the direction of the arrow *b*, Fig. 4, illustrating a portion of the raceway, the work-rest, the presser foot, the guide-way, the button holder, the button ejector, and the 40 primary and secondary loopers. Fig. 20 is a perspective view taken in the direction of the arrow *b* (Fig. 4) illustrating the button holder and its spring. Fig. 21 is a detail section, partly in elevation, taken on line 45 H—H, Fig. 2, a button and the upper of a boot being shown in connection therewith, the upper being shown in section. Fig. 22 is a perspective view of the guide-way and work-rest. Figs. 23 to 29, inclusive, are enlarged 50 illustrative views of the button, illustrating in connection therewith the manner in which the same is attached to the upper by the thread. Fig. 30 is a detail sectional plan of the detent, together with a portion 55 of the raceway and rocker frame to which said detent is pivoted, taken on line K—K, Fig. 21.

Like numerals refer to like parts throughout the several views of the drawings. 60 In the drawings, 35 is the frame of the machine, 36 the driving shaft to which the cams for operating the different mechanisms are fastened. The driving shaft 36 is driven by a pulley 37 which is connected to or detached from the driving shaft by a clutch

38 operated by means of a clutch slide 39 which is connected by means of a treadle-rod 40 to a suitable treadle (not shown in the drawings).

The buttons 41, 41 are placed in a suitable 70 hopper 42 and are fed down the raceway 43 from said hopper, said buttons being fed into the raceway by means of a brush feed located within the hopper, well known to those skilled in this art, and, therefore, not 75 illustrated in the drawings, a rocking motion, however, being imparted to said brush feed by means of a link 44 (Fig. 18) which is connected to a lever 45 pivoted on the shaft 135 and having a cam roll 47 journaled 80 thereon and projecting into a cam groove 87 in the cam blank 74, this cam groove 87 being utilized to drive both the brush rocking mechanism and the raceway rocking mechanism hereinafter described. 85

The buttons 41 descend the raceway until they arrive at the bottom thereof, the lowermost button 41' being stopped by contact with a spring-pressed detent 49 which is pivoted to a pin 50 fast to ears 51, 51 forming a portion of the raceway rocker frame 52, which rocker-frame is fastened to a rock-shaft 53 journaled to rock in bearings 54, 54 forming a portion of the frame of the machine. A spring 55 encircles the pivotal pin 90 50 and bears against the detent 49 so as to hold it in contact with the lowermost button 41' upon the raceway 43 (see Fig. 21). The lowermost button 41' is removed from the raceway, as hereinafter more fully described, 95 to be carried forward and sewed to the upper by the needle 56 which has imparted to it, to adapt it to perform its different functions, a combined reciprocating and lateral movement. 100

105 Referring to Figs. 2, 5, 6 and 7, it will be seen that the eye-pointed needle 56 is fastened to a needle bar 57 which is adapted to slide longitudinally thereof in bearings 58, 58 formed upon a rocker-arm 59. The needle bar 57 is connected by a link 60 to a rocker-arm 61 fast to a rock-shaft 62 which is journaled to rock in suitable bearings in the frame of the machine (Figs. 5 and 7). To the opposite end of the rock-shaft 62 from that to which the arm 61 is fastened a rocker-arm 63 is fastened, and to this arm 63 is attached a cam slide 64 slotted at 65 to straddle the driving shaft 36. A cam roll 66 is rotatably mounted upon the cam slide 64 and is driven by a cam 67, so that it will be readily seen that the cam 67 imparts a rocking movement to the arms 63 and 61 and through the link 60 imparts a vertical reciprocating movement to the needle-bar 57. 110

115 A lateral movement is imparted to the eye-pointed needle 56 and to its needle bar 57 by rocking the rocker-arm 59, upon which the needle bar is slidably mounted and to accomplish this rocking movement of the 120 125

rocker-arm 59 the same is fastened to a rock-shaft 68 journaled to rock in suitable bearings in the frame of the machine and having fastened to the opposite end thereof to that 5 to which the rocker arm 59 is fastened a rocker-arm 69 (Fig. 8). A rocking motion is imparted to the arm 69 by a cam lever 70 which is pivoted to a stud 71 fast to the frame of the machine, and which has ro- 10 tatably mounted upon its upper end a cam roll 72 which projects into a cam slot 73 in the cam blank 74. The lower end of the lever 70 has a pin 75 fast thereto and mounted upon said pin 75 is a sliding block 76 which 15 projects into a slot 77 formed in the arm 69.

A spring 78 bears against one side of the rocker-arm 69, the same being coiled around a screw 79 fast to the frame of the machine, so that the arm 69 is normally held by said 20 spring in contact with an adjusting screw 80 which has screw-threaded engagement with a lever 81 which is rigidly fastened to the rock-shaft 53. The lever 81 has an upwardly extending arm 82 provided with a 25 slot 83 through which a clamp-screw 84 projects. The clamp-screw 84 has screw-threaded engagement with an arm 85 which is loosely mounted on the rock-shaft 53 and has at its outer free end a cam roll 86 ro- 30 tatably mounted thereon and projecting into a cam groove 87 formed in the cam blank 74.

The adjusting screw 80 is for the purpose of adjusting the needle laterally thereof until it shall aline perfectly with the center of 35 the eye of the lowermost button 41' in the raceway, so that when the needle ascends, the same shall pass through the eye of said button preparatory to removing the same from the raceway upon the lateral rocking move- 40 ment of said needle. The adjustment furnished by the clamp-screw 84 is for the purpose of increasing or diminishing, as may be desired, the feed of the stock so that buttons may be spaced at different distances on dif- 45 ferent uppers, as may be desired.

It will be noted that the cam slot 73 is of much greater width at one portion thereof than at another, the object of this being to allow the lever 70 to rock when the lever 81 50 is adjusted by means of the clamp-screw 84 and clamp-nut 84', thus moving the cam roll 72 toward or away from the center of the shaft 36 according to the direction in which the lever 81 is rocked or adjusted, the point 55 to which the needle is rocked laterally being always the same, but the point from which it starts, varying, to give different distances between the buttons, according to the position of the lever 81, the screw 80, the rocker- 60 arm 69 and the rocker-arm 59. To illustrate, if the clamp-nut 84' is loosened and the lever 81 moved toward the left at its lower end, Fig. 8 the clampnut 84' then being tightened, this will move the rocker-arm 69 65 toward the left and consequently the rocker-

arm 59 and the needle and needle bar sup- 70 ported thereon toward the left or nearer to the point to which the button is to be eventu- 75 ally fed.

When the rocker-arm 69 is moved toward the left, the lever 70, at its lower end, will be moved toward the left and at its upper end will be moved toward the right, carrying the cam-roll 72 outwardly from the center and, therefore, when the same is rocked by the 75 cam 73 coming in contact therewith as the cam blank 74 rotates in the direction of the arrow (Fig. 8), it will be seen that less throw will be given to the lever 70 and to the rocker arm 69 and rocker arm 59 and, therefore, to 80 the needle bar and needle. If, on the contrary, the clamp-nut 84' is loosened and the upper end of the lever 81 moved toward the left, said lever 81, at its lower end, will be moved outwardly, allowing the rocker-arms 85 69 and 59, with the needle and needle bar, to move toward the right (Figs. 7 and 8), thus moving the lower end of the lever 70 toward the right and the upper end thereof toward the left, together with the cam roll 72 there- 90 on, so that when the rocking of the lever 70 is accomplished by the cam path 73, a greater movement will be imparted to the rocker-arms 69, 59, needle bar and needle. Thus by 95 adjusting the clamp-screw 84 toward the right or left (Fig. 8) a less or greater lateral movement, respectively, of the needle and, therefore, a correspondingly less or greater movement of the feed of the stock will be obtained.

It will be seen by the construction herein- 100 before described that when the rocker-arm 59 and needle 56 are set for a certain feed, by adjusting the lever 81 by means of the clamp-screw 84 and clamp-nut 84' the raceway will 105 be correspondingly moved to preserve its alignment with the needle, for the reason that the raceway 43 is fast to the rock-shaft 53 to which the lever 81 is fastened, so that any adjustment of the lever 81 necessarily 110 adjusts the raceway as though it were a part thereof and, therefore, the raceway and needle will be moved to the same extent and in the same direction when the adjustment hereinbefore described by means of the 115 clamp-screw 84 and clamp-nut 84' is effected.

By reference to Figs. 2, 10, 19 and 21, it will be seen that the upper 88 is pressed 120 against a work-rest 89 by a presser foot 90 which consists of a hollow rectangular portion 91 fastened to a slide 92, the lower end of which is preferably cylindrical in form and extends through a collar 93 resting upon the outer end of a rocker-arm 94 which is fastened to a rock-shaft 95. A spring 96 is 125 interposed between a shoulder 97 upon the slide 92 and the collar 93. A rocking motion is imparted to the arm 94 and rock- 130 shaft 95 by a rocker-arm 98 fast to the rock- shaft 95 and connected to a cam slide 99.

which is slotted at 100 to straddle the shaft 36. A cam roll 101 is mounted upon the slide 99 and projects into a cam slot 102 in the cam blank 103, so that it will be seen that the presser foot is pressed with a spring pressure against the under side of the work shaft 95 and connected to a cam slide 99 upwardly, thus rocking the arms 98 and 94 upwardly and moving the slide 92 upwardly, together with the hollow rectangular portion 91, and pushing said rectangular portion against the under side of the work-rest 89, through the spring 96, so that the material of the upper 88 will be clamped against the under side of the work-rest 89 with a spring pressure. Along the upper face of the rectangular portion 91 of the presser foot are two ribs 104, 104 which bear directly against the under side of the upper 88, the object of this construction of the upper portion of the presser foot being to make room for the button-fly 105 (Fig. 21).

The lowermost button upon the upper is often very close to the point where the button-fly and vamp are attached to that portion of the upper to which the buttons are sewed and, therefore, where the presser foot is flat across its entire surface, the corded button-fly becomes inserted between the presser foot and the work-support, thus leaving the comparatively thin upper to which the button is to be sewed, unsupported and unclamped by the presser foot, resulting, oftentimes, in the needle missing a button, with the result that the first button is not sewed to the upper.

By the construction of my machine, in which the ribs form a narrow raised portion upon each side of the slot 106, which extends longitudinally of the presser foot and through which the needle passes, it will be seen that the comparatively thin or single thickness material of the upper 88 will be clamped firmly against the work-rest 89 by the raised portions 104, 104 upon the presser foot 90, while the button fly portion 105 finds room beneath the upper and above the top of the presser foot to be fed along without interfering with the sewing of the button upon the upper 88, and this is true whether it be a right or a left hand upper.

The work-rest 89 is fastened to the overhanging arm 35' of the frame and has formed integral therewith, or, if preferred, attached thereto a guide-way 107 in which there is a groove or slot 108 extending longitudinally of the guide-way 107 from the bottom of the raceway 43, and in this grooved portion the head of the button rests as it is fed from the raceway away from the operator. A vertical flange 109 extending adjacent to the slot 108 forms a support for the eye of the button as it is being fed from the raceway to the button holder 110. Said button holder is illustrated in Fig. 20 and

consists of two arms 111, 111 pivoted at 112, 112 to the work-support. The arms 111, 111 are connected together by a cross-bar 113 which is extended toward the front of the machine to form a tongue 114, beneath which the head of the button passes as it is carried from the raceway to a slot 115 at one side of the cross-bar 113.

The slot 115 opens out of one side of the horizontal flange 116 upon said button holder and the holder is pressed downwardly upon the head of the button by a spring 117 which is coiled around a screw 118 fast to the work-rest, the free end of the spring bearing against the flange 116.

As hereinafter more fully described in the general operation of the machine, a primary looper 119 and an independent secondary looper 120 are employed to manipulate the primary and secondary loops of thread. The primary looper 119 has a rocking motion imparted thereto and also a motion to one side; the secondary looper 120 has a rocking motion only imparted thereto. The mechanism for imparting the rocking and side movement to the primary looper will now be described.

The looper 119 consists of a wire having a hook 121 at its free end. Said looper projects through a rocker-shaft 122 and is adjustably fastened thereto by means of a setscrew 123. By reference to Fig. 14 it will be seen that the rocker-shaft 122 is journaled to rock in suitable bearings in the arm 35'. A rocking motion is imparted to the shaft 122 by an arm 124 which is fast to the rock-shaft 122 and has sliding engagement with a pin 125 fast to a cam slide 126 which is slotted at 127 to straddle the shaft 36 and has a cam roll 128 mounted thereon and projecting into a cam path 129 in one face of the cam blank 130. It will be seen that when the cam slide 126 is reciprocated, it will, through the pin 125, impart a rocking motion to the arm 124, to the rock-shaft 122 and to the primary looper 119. A spring 131 encircles the shaft 122 and bears at one end against the arm 35' and at the other end against the hub of the arm 124, thus holding said arm always in contact with the cam path 132 formed upon the edge of the cam blank 130. The irregularity of this cam path imparts a reciprocatory movement to the arm 124 which is held thereagainst by the spring 131 and, therefore, imparts a reciprocatory movement to the shaft 122 in its bearings in the frame and a side movement to the primary looper 119.

The secondary looper 120 has a rocking motion imparted thereto by the mechanism illustrated in Fig. 15. Said looper consists of a wire bent to form a hook 133 at its free end and adjustably fastened by a screw 134 to a rocker-shaft 135 journaled to rock in bearings in the arm 35' of the frame 35. The rocker-shaft 135 has an arm 136 fast

thereto which is pivotally connected to a cam slide 137 slotted at 138 to straddle the shaft 36, a reciprocatory motion being imparted to said cam slide by a cam-roll 139 mounted thereon and projecting into a cam groove 140 in the cam blank 130.

At a certain time in the operation of the machine, the button is ejected from beneath the button holder and out of the groove in the guide-way and through the secondary loop and is moved from a position in which the eye is horizontal to a position in which said eye is substantially vertical. The mechanism for performing this operation is particularly illustrated in Figs. 16, 17 and 19 and consists of a button ejector 141, said button ejector consisting of a slide 142 adapted to slide at its forward end in a slot 143 in the frame arm 35', the rear end of said slide having an enlarged block portion 144 thereon which is slidably supported upon the rock-shaft 135. A spring 145 encircles the shaft 135 and bears at one end against the block 144 and at the other end against the arm 35', thus holding the block portion 144 of the slide 142 against a cam 146 which is fast to the shaft 36.

An arm 147 extends downwardly from the slide 142 and has a right angle projection 148 thereon which is beveled at 149 on the front end thereof, the lower portion of said arm being adapted to slide upon the work-rest 89 between the arms 111, 111 of the button holder and thus to engage the head of the button 41' as it is held beneath the button holder in the groove 108 of the guide-way 107. As the slide 142 is moved forwardly the beveled end 149 of the arm 147 engages the head of the button 41' and pushes said button out of the groove 108 and out of the slot 115 in the button holder and tips said button until the eye assumes a vertical position, at the same time pushing the button through the secondary loop, all as hereinafter more fully set forth.

At a certain time in the operation of the machine, it is necessary that the slack in the thread should be taken up by a take-up mechanism, and this take-up mechanism is particularly illustrated in detail in Fig. 13, and consists of a take-up lever 150 fast to a rock-shaft 151 journaled to rock in bearings in the frame 35, and to which a rocking motion is imparted by an arm 152 fast thereto and connected to a cam slide 153 slotted at 154 to straddle the shaft 36. A cam roll 155 is rotatably mounted on the cam slide 153 and projects into a cam groove 156 in the cam blank 103, so that it will be seen that a rocking motion will be imparted to the rock-shaft 151 when a reciprocatory motion is imparted to the cam slide 153 by the cam 156, thus taking up the slack in the thread at the desired time in the operation of the machine.

It is necessary in the operation of the machine that at certain times the thread, as it passes from the spool to the needle, should be locked therebetween, in order to properly manipulate the same in the taking up of the slack and in drawing taut the primary and secondary loops, and for this purpose the thread-clamp 157 is provided, the same being particularly illustrated, together with the mechanism by which it is operated, in Figs. 11 and 12, and 13. This thread clamp consists of a slide 158 having a right angle upward extension or clamping jaw 159, said clamping jaw extending upwardly adjacent to the frame 35 and bracket 160. The thread 161 extends through an eye 162 in the slide 158, thence upwardly between the clamping jaw 159 and frame 35 and between the clamping jaw 159 and bracket 160 through a thread-eye 163, through another thread-eye 164, both of said thread-eyes fast to the bracket 160. Said thread then extends through a slot or eye 165 in the upper end of the take-up lever 150 and thence through the guide-eye 166 formed in the upper end of a spring 167 fast to the lever 150 (see Figs. 2 and 13).

The slide 158 is moved toward the right or left (Fig. 11) to clamp the thread or to unclamp the same from the frame of the machine by a lever 168 pivoted at 169 to the frame 35, and connected by a spring 170 to the slide 158. A rocking motion is imparted to the lever 168 by a link 171 which is connected to the lower end of a lever 172 pivoted at 173 to the frame of the machine and having a cam roll 174 mounted upon its upper end and projecting into a cam groove 175 in the cam blank 103.

It will be seen that when the lever 172 is rocked by the cam 175, the link 171 connected to said lever and to the lever 168, will rock said lever and move the slide 158 toward the right, thus clamping the thread 161 between the right angle portion 159 and the frame by a spring pressure imparted thereto through the spring 170, and thus the thread will be clamped between the needle and the spool at the proper time to hold the thread while the take-up lever or needle is tightening the stitch, and taking up the slack.

A rocking motion is imparted to the race-way and to the button hopper by the cam 87, lever 85 and rock-shaft 53 to which the lever 85 is fastened by means of the clamp-bolt 84 and clamp-nut 84', and the lever 81 which is rigidly fastened to said rock-shaft 53, (Fig. 8).

The objects of rocking the raceway are first to move the same at its lowermost end away from the primary hook as said hook swings toward the operator to take the primary loop of thread, and second, to jar the buttons on the raceway so that they will

more readily slide into place and thus insure the lowermost button upon the raceway being in position so that the eye thereof shall receive the needle as it moves upwardly through the material with the primary loop.

5 The general operation of the mechanism hereinbefore specifically described is as follows: Assuming the parts to be in the positions illustrated in Figs. 1, 2, 3 and 4, the operator ships the clutch to throw the pulley 10 into operative connection with the driving or cam shaft 36. The needle rises through the upper 88 of the shoe and through the eye of the button 41', said button being at 15 that time the lowermost button in the raceway 43, thus carrying the thread in the form of a primary loop *d* through the eye 41² of the button 41', as illustrated in perspective diagrammatic view in Fig. 23. At this time 20 the upper is clamped between the presser foot 90 and the bottom of the work-rest 89. The needle having passed upwardly through the eye of the button, the presser foot 90 descends slightly, thus releasing the upper 25 so that it may be fed. A rocking motion is now imparted to the rocker-arm 59 by the mechanism hereinbefore described, and this moves the needle bar 57 and needle 56 toward the left (Fig. 2), thus removing the button 30 41' from the lower end of the raceway, pushing aside the detent 49 and feeding the button along the guide-way 107, the head of the button sliding in the groove 108 in said guide-way while the eye of said button 35 is supported upon the vertical flange 109 of said guide-way, the needle passing along laterally thereof in the slot 106 in the presser foot 90 and in the slot 176 in the work-rest 89 to the full extent of the button feed or 40 distance between the centers of the button eyes.

The button, as it leaves the raceway, passes under the inclined under edge of the tongue 114 of the button holder 110, and at the end 45 of the movement of the needle the button is brought into alinement with the slot or opening 115 in the flange 116 of said button holder, the spring 117 allowing the button holder to yield while the button head is 50 moving therebeneath and acting to press the button holder downwardly upon the button head, so that when the button head arrives in alinement with the slot 115, said button holder will be pressed downwardly 55 and the head of the button will project upwardly slightly into the slot 115, all as illustrated in Figs. 16 and 19. The upper is now clamped and the needle descends and throws out the primary loop *d* of thread, on the 60 right hand side of the needle. This primary loop is taken from the needle by the primary looper or hook 119, which is moved forwardly toward the operator, entering the primary loop at the right hand side of 65 the needle. Said primary loop is held by

the looper 119 while the needle descends through the material to its lowest point, the primary loop *d* being carried by the primary looper toward the operator and slightly to the left of the line of feed, as shown in Fig. 70 24. The needle having descended to its lowest point then moves toward the operator the length of the short stitch. The needle then moves upwardly through the upper 88, outside and in front of the eye of the button 75 41² and through the first loop *d*, which is at this time held by the primary looper and spread in the path of the needle by reason of the forward and side movement of said primary looper.

When about half way up the needle rests and the primary looper moves still farther sidewise to the left of the line of feed and then moves backwardly from the operator, releasing the primary loop of thread from 80 the hook of the looper and leaving the thread around the needle, as illustrated in Fig. 25, in so far as the loops of thread and the button are concerned. The thread clamp 157 then clamps the free end of the thread and 85 the needle continues its upward movement and draws up all of the slack of the thread of the first stitch. The thread clamp is then released and the needle passes downwardly, throwing out a secondary loop *f* to one side 90 of the needle, so that the same may be taken by the secondary hooked looper 120, which enters the loop thrown out by the needle and draws it out in the direction of the line of feed to form a triangle, as shown in Fig. 26, 95 the triangular formation of the loop *f* being obtained by the thread being held by the needle at the angle *f'* of the triangle, said loop being held by the secondary looper 120 at the angle *f''* of the triangle and by the material of the upper at the angle *f'''* of the upper, where the secondary loop passes through 100 said upper. The secondary hook now moves slightly toward the front or toward the operator, the needle descends slightly, these 110 two operations loosening up on the thread, and the button is then pushed through the triangle by the button ejector or pusher 141, which pushes the button from under the button holder 110 out of the guide-way 107 and 115 through the secondary loop *f*, simultaneously tipping the button until the eye 41² is moved from a horizontal position to a substantially vertical position, as illustrated in Fig. 27. Now the needle descends to its lowest position and as it descends the thread supply 120 is clamped and held tightly. The secondary hook 120 stands in a rigid position while the thread take-up lever 150 moves forward and pulls the thread while said thread is still 125 held by the secondary looper 120 and while it is rigidly clamped by the thread clamp 157, thus taking up all of the remaining slack of the first stitch and drawing the primary and the secondary loops and the eye of 130

the button down near the hole made by the needle in its first upward movement, as shown in Fig. 27, leaving the button eye at right angles with the line of feed and drawing said primary and secondary loops tight together near the first hole made by the needle in its first ascent. The secondary loop is now cast off of the secondary looper, the take-up moves a second time 10 to draw up the slack of the second stitch or to draw up the slack of the second loop and to draw the loops tightly down against each other and around the eye of the button, as illustrated in Figs. 28 and 29, 15 successively, forming a flat knot. The primary loop of the flat knot passes through the eye of the button and the secondary loop of the knot passes through the primary loop, around the eye of the button outside thereof 20 and around the primary loop where it passes up through the leather.

The particular manner, hereinbefore described, in which the thread is held and tightened by the looper and by the take-up, 25 respectively, prevents any puckering or wrinkling of the upper between the buttons and the thread can be cut between any two buttons without any danger of the button becoming detached from the upper, as the 30 loop within a loop, one of said loops passing through the eye of the button and the other around the same, forms an independent locking flat knot, one part of which locks the other against becoming detached from the 35 button or from the upper.

Particular attention is called to the movement of the primary looper 119, which has a five motion rotary movement, as hereinbefore described, viz., first, the hook moves toward the operator and past the needle on the right hand side of the needle; second, said looper takes a side motion to the left, directly between the needle and the operator; third, a second side motion to the left and past the needle and line of feed; fourth, said hook is oscillated backwardly or away from the operator and past the needle on the left hand side of the needle; and fifth, the same is moved toward the right back of the needle to its first position.

Having thus described my invention, what I claim and desire by Letters Patent to secure is:

1. In a machine for sewing buttons to the upper of a boot or shoe, means for holding a button, instrumentalities adapted to pass a primary loop of thread through said upper and through the eye of said button and for feeding the upper and the button the total distance desired between the centers of the eyes of two adjacent buttons while the needle is through the eye of the button, said instrumentalities adapted to pass a secondary loop of the same thread through 55 said upper and through said primary loop,

means to pass said button through said secondary loop, and means for drawing the secondary loop in the direction in which the material is fed.

2. In a machine for sewing buttons to the upper of a boot or shoe, means for holding a button, instrumentalities adapted to pass a primary loop of thread through said upper and through the eye of said button and for feeding the upper and the button the total distance desired between the centers of the eyes of two adjacent buttons while the needle is through the eye of the button, said instrumentalities adapted to subsequently pass a secondary loop of the same thread through said upper and through said primary loop, means for drawing the secondary loop in the direction in which the material is fed, means to pass said button through said secondary loop, means for clamping the free end of the thread, said instrumentalities adapted to draw up the slack thread of the first loop while said secondary loop is being held.

3. In a machine for sewing buttons to the upper of a boot or shoe, means for holding a button, instrumentalities adapted to pass a primary loop of thread through said upper and through the eye of said button and for feeding the upper and the button the total distance desired between the centers of the eyes of two adjacent buttons while the needle is through the eye of the button, said instrumentalities adapted to subsequently pass a secondary loop of the same thread through said upper and through said primary loop, means for drawing the secondary loop in the direction in which the material is fed, means to pass said button through said secondary loop, means for clamping the free end of the thread, and means for drawing up the slack thread of the first loop, while said secondary loop is being held, whereby the eye of the button is turned at right angles to the line of feed, adjacent to the hole made by the first rise of the needle.

4. The combination, in a machine for sewing shank eyed buttons to boots, shoes, gaiters or other fabrics, of mechanism for holding a button in position, mechanism for clamping and unclamping the fabric, a needle, and mechanism adapted to impart a reciprocatory motion thereto, mechanism adapted to move the needle laterally thereof while the needle is through the eye of the button, whereby the fabric and the button are moved the total distance desired between the centers of the eyes of two adjacent buttons, and instrumentalities adapted to subsequently form the stitches, whereby the button is attached to the fabric.

5. The combination, in a machine for sewing shank-eyed buttons to boots, shoes, gaiters and other fabric, of means for holding a button in position, mechanism for

clamping and unclamping said fabric, an eye pointed needle, and operating mechanism to impart a reciprocatory and lateral movement thereto, whereby a primary loop 5 may be passed through the eye of said button and said fabric may be fed while the needle is through the eye of the button and whereby a secondary loop of thread may be subsequently passed through said fabric 10 at one side of said eye, a primary looper, and mechanism adapted to impart a five motion movement thereto around the median axial line of said needle, viz., 1st, to rock said looper toward the front of said machine and 15 past the needle on the right hand side thereof; 2d, to impart to said looper a side motion to the left directly between the needle and the front of the machine; 3d, to impart to said looper a second side movement to the 20 left and past the needle; 4th, to oscillate said looper backwardly and past the needle on the left hand side thereof; and 5th, to return said looper to its first position back of the needle relatively to the front of the 25 machine, a secondary looper, mechanism adapted to move said secondary looper to take the secondary loop from said needle, and means to push said button through said secondary loop.

30 6. The combination, in a machine for sewing shank-eyed buttons to boots, shoes, gaiters and other fabric, of means for holding a button in position, mechanism for clamping and unclamping said fabric, an eye pointed needle and operating mechanism to impart a reciprocatory and lateral movement thereto, whereby a primary loop 35 may be passed through the eye of said button and said fabric may be fed and whereby a secondary loop of thread may be subsequently passed through said fabric at one side of said eye, a primary looper, and mechanism adapted to impart a five motion movement thereto around the median axial line 40 of said needle, viz., 1st, to rock said looper toward the front of said machine and past the needle on the right hand side thereof; 2d, to impart to said looper a side motion to the left directly between the needle and 45 the front of the machine; 3d, to impart to said looper a second side movement to the left and past the needle; 4th, to oscillate said looper backwardly and past the needle on the left hand side thereof; and 5th, to 50 return said looper to its first position back of the needle relatively to the front of the machine, an independent secondary looper, mechanism adapted to move said secondary looper to take the secondary loop from said 55 needle, means to push said button through said secondary loop, said means for moving the secondary looper also adapted to hold said secondary looper rigidly in position, and a take-up mechanism, whereby all of the 60

slack of the first loop may be drawn up while 65 the secondary loop is held by the secondary looper back of the needle and the eye of said button drawn down against the fabric, with the button in an upright position and with the button eye at right angles to the 70 line of feed of the material.

7. In a machine for sewing buttons to the upper of a boot or shoe, means for holding a button, instrumentalities adapted to pass a primary loop of thread through said upper and through the eye of said button, means to move said upper and button the total distance desired between the centers of the eyes of two adjacent buttons while the needle is through the eye of said button, 80 means to subsequently hold said primary loop while said instrumentalities pass a secondary loop of the same thread through said upper and through said primary loop, means to hold said secondary loop, and 85 means to pass said button through said secondary loop.

8. In a machine for sewing buttons to the upper of a boot or shoe, means for holding a button, a needle, mechanism to impart a 90 reciprocatory motion to said needle, whereby a primary loop of thread may be carried through said upper and through the eye of said button, a primary looper, mechanism to impart a rocking motion to said looper to receive said primary loop while said needle retreats, mechanism to impart a lateral movement to said looper, mechanism to move said needle laterally thereof after it has retreated through the upper, whereby upon a 100 second forward movement of said needle through the upper, a secondary loop of said thread is passed through said upper and primary loop, an independent secondary looper, mechanism to impart a rocking motion to said secondary looper to receive said secondary loop while said needle retreats a second time, and means to pass said button through said secondary loop.

9. In a machine for sewing buttons to the 110 upper of a boot or shoe, means for holding a button, a needle, mechanism to impart a reciprocatory motion to said needle, whereby a primary loop of thread may be carried through said upper and through the eye of 115 said button, a primary looper, mechanism to impart a rocking motion to said looper to receive said primary loop while said needle retreats, mechanism to impart a lateral movement to said looper, mechanism to move said 120 needle laterally thereof after it has retreated through the upper, whereby upon a second forward movement of said needle through the upper, a secondary loop of said thread is passed through said upper and primary 125 loop, an independent secondary looper, mechanism to impart a rocking motion to said secondary looper to receive said sec-

ondary loop and open the same in alinement with said button, and means to pass said button through said secondary loop.

10. In a machine for sewing buttons to the upper of a boot or shoe, means for holding a button, a needle, mechanism to impart a reciprocatory motion to said needle, whereby a primary loop of thread may be carried through said upper and through the eye of said button, a primary looper, mechanism to impart a rocking motion to said looper to receive said primary loop while said needle retreats, mechanism to impart a lateral movement to said looper, mechanism to move said needle laterally thereof after it has retreated through the upper, whereby upon a second forward movement of said needle through the upper, a secondary loop of said thread is passed through said upper and primary loop and said primary loop dropped by said primary looper, means to clamp said thread while said needle is moving upward the second time, an independent secondary looper, and mechanism to impart a rocking movement thereto to receive said secondary loop and open the same in alinement with said button, means to push said button through said secondary loop, a take-up, and mechanism to move the same to tighten the thread and take up the slack of the first loop while said secondary loop is on the secondary looper, and again to tighten the loops around each other and the eye of the button after the secondary loop has been cast off of the secondary looper.

11. In a machine for sewing buttons to the upper of a boot or shoe, means for holding a button, a needle; mechanism to impart a reciprocatory motion to said needle, whereby a primary loop of thread may be carried through said upper and through the eye of said button, a primary looper consisting of a rocker-arm with its free end bent to form a hook, mechanism to impart a rocking motion to said primary looper, to receive said primary loop while said needle retreats, mechanism to impart a lateral movement to said looper, mechanism to move said needle laterally thereof after it has retreated through said upper, whereby upon a second upward movement of said needle through the upper a second loop of thread is passed through said upper and primary loop, a secondary looper consisting of a rocker-arm with its free end bent in the opposite direction to that of said primary looper, mechanism to impart a rocking motion to said secondary looper to receive said secondary loop while said needle retreats a second time, means to pass said button through said secondary loop, and means to tighten said loops around each other and around the eye of the button.

12. In a machine for sewing a button to the upper of a boot or shoe, a raceway, a

guide-way adjacent to the lower end of said raceway and adapted to guide said button, a spring-pressed button holder located above said guide-way, a needle, and instrumentalities adapted to impart a vertical and a lateral motion to said needle, whereby the same may be projected through the eye of said button and said button fed from said raceway while said needle is through the eye of said button along said guide-way and beneath said holder.

13. In a machine for sewing a button to the upper of a boot or shoe, a raceway, a spring-actuated detent at the bottom of said raceway, a guide-way adjacent to the lower end of said raceway adapted to guide said button, a spring-pressed button holder located above said guide-way, a needle and instrumentalities adapted to impart a vertical and a lateral motion to said needle, whereby the same may be projected through the eye of the lowermost button in said raceway, and said button moved past said detent, from said raceway along side guide-way and beneath said holder, while said needle is through the eye of said button.

14. In a machine for sewing a button to the upper of a boot or shoe, a raceway, a guide-way adjacent to the lower end of said raceway and adapted to guide said button, a spring-pressed button holder located above said guide-way, a needle, instrumentalities adapted to impart a vertical and a lateral motion to said needle, whereby the same may be projected through the eye of said button and said button fed from said raceway along said guide-way and beneath said holder while said needle is through the eye of said button, and means to eject said button from beneath said button holder and from said guideway for the purpose specified.

15. In a machine for sewing a shank-eyed button to the upper of a boot or shoe, a guide-way adapted to receive the head of said button, an eye-pointed needle, mechanism adapted to impart a reciprocatory and lateral movement to said needle, a spring-pressed holder adapted to bear against said button head and hold the same stationary in said guide-way after said button has been fed by said needle longitudinally of said guide-way and beneath said holder, and means to eject said button from said guide-way and transversely thereof for the purpose specified.

16. In a machine for sewing a shank-eyed button to the upper of a boot or shoe, a guide-way adapted to receive the head of said button, an eye-pointed needle, mechanism adapted to impart a reciprocatory and lateral movement to said needle, a spring-pressed holder adapted to bear against said button head and hold the same stationary in said guide-way after said button has been

fed by said needle longitudinally of said guide-way and beneath said holder, and means to eject said button from said guide-way and transversely thereof and simultaneously rock said button, whereby the eye thereof shall be moved from a horizontal to a vertical position.

17. In a machine for sewing a button to the upper of a boot or shoe, a work-support provided with a slot extending longitudinally thereof and a guide-way on said work-support adapted to receive and guide the head of a button and extending parallel with and adjacent to said slot, an eye pointed needle, mechanism adapted to impart a reciprocatory and lateral movement to said needle, a spring-pressed holder adapted to bear against said button head and hold the same stationary in said guide-way after said button has been fed by said needle longitudinally of said guide-way and beneath said holder, a presser foot, and means to hold said presser foot against the under side of said work-support with a spring pressure.

18. In a machine for sewing a button to the upper of a boot or shoe, a work-support provided with a slot extending longitudinally thereof and a guide-way on said work-support adapted to receive and guide the head of a button and extending parallel with and adjacent to said slot, an eye pointed needle, mechanism adapted to impart a reciprocatory and lateral movement to said needle, a spring-pressed holder adapted to bear against said button head and hold the same stationary in said guide-way after said button has been fed by said needle longitudinally of said guide-way and beneath said holder, a presser foot, and instrumentalities adapted to move said presser foot away from said work-support and to press the same thereagainst with a spring pressure, said presser foot having a slot therein in alignment with the slot in said work-support.

19. In a machine for sewing a button to the upper of a boot or shoe, a work-support provided with a slot extending longitudinally thereof, a guide-way on said work-support adapted to guide a button, extending parallel with and adjacent to said slot, a presser foot, instrumentalities adapted to move said presser foot away from said work-support and to press the same thereagainst with a spring-pressure, a raceway, the lower end thereof adjacent to said guide-way; in combination with a needle and instrumentalities adapted to impart a vertical and a lateral motion to said needle, whereby the same may be projected through an upper held between said presser foot and work-support and through the eye of a button on said raceway, and said upper and button fed longitudinally of said guide-way while the needle is through the eye of said button.

20. In a machine for sewing a button to

the upper of a boot or shoe, a work-support provided with a slot extending longitudinally thereof and a guide-way on said work-support, adapted to guide a button and extending parallel with and adjacent to said slot, a presser foot, instrumentalities adapted to move said presser foot away from said work-support and to press the same thereagainst with a spring pressure, a spring-pressed button holder pivoted above said work-support, and a raceway, the lower end thereof adjacent to said guide-way; in combination with a needle and instrumentalities adapted to impart a vertical and a lateral motion to said needle, whereby the same may be projected through an upper held between said presser foot and work-support and through the eye of a button on said raceway, and said upper and button fed longitudinally of said guide-way while the needle is through the eye of said button until the head of said button passes beneath said button holder.

21. In a machine for sewing a button to the upper of a boot or shoe, a work-support provided with a slot extending longitudinally thereof and a guide-way on said work-support adapted to guide a button and extending parallel with and adjacent to said slot, a presser foot, instrumentalities adapted to move said presser foot away from said work-support and to press the same thereagainst with a spring pressure, a spring-pressed button holder pivoted above said work-support, and a raceway, the lower end thereof adjacent to said guide-way; in combination with a needle, instrumentalities adapted to impart a vertical and a lateral motion to said needle, whereby the same may be projected through an upper held between said presser foot and work-support and through the eye of a button on said raceway and said upper and button fed longitudinally of said guide-way until the head of said button passes beneath said button holder, a button ejector, and instrumentalities adapted to move the same into contact with the head of said button and transversely of said guide-way, whereby said button may be ejected from said guide-way and from beneath said button holder for the purpose specified.

22. In a machine for sewing a button to the upper of a boot or shoe, a work-support provided with a slot extending longitudinally thereof and a guide-way on said work-support adapted to guide a button and extending parallel with and adjacent to said slot, a presser foot, instrumentalities adapted to move said presser foot away from said work-support and to press the same thereagainst with a spring-pressure, a spring-pressed button holder pivoted above said work-support, and a raceway, the lower end thereof adjacent to said guide-way; in com-

- bination with a needle, instrumentalities adapted to impart a vertical and a lateral motion to said needle, whereby the same may be projected through an upper held between 5 said presser foot and work-support and through the eye of a button in said raceway and said upper and button fed longitudinally of said guide-way until the head of said button passes beneath said button holder, a button ejector consisting of a slide and means to impart a reciprocatory motion to said slide transversely of said guide-way and into contact with the head of said button, whereby said button may be ejected 10 from said guide-way and from beneath said button holder for the purpose specified.
23. In a machine for sewing a button to the upper of a boot or shoe, a work-support provided with a slot extending longitudinally thereof and a guide-way on said work-support adapted to guide a button and extending parallel with and adjacent to said slot, a presser foot, instrumentalities adapted to move said presser foot away from said 15 work-support and to press the same thereagainst with a spring pressure, a spring-pressed button holder pivoted above said work-support, and a raceway, the lower end thereof adjacent to said guide-way; in combination with a needle, instrumentalities adapted to impart a vertical and a lateral motion to said needle, whereby the same may be projected through an upper held between 20 said presser foot and work-support and through the eye of a button on said raceway, and said upper and button fed longitudinally of said guide-way until the head of said button passes beneath said button holder, a button ejector consisting of a slide, 25 the forward end of said slide being beveled, and means to impart a reciprocatory motion to said slide transversely of said guide-way and into contact with the head of said button, whereby said button may be ejected 30 from said guide-way and from beneath said button holder, and simultaneously rock said button until the eye thereof shall be moved 35 from a horizontal to a vertical position.
24. In a machine for attaching a button to the upper of a boot or shoe, a needle and needle bar, a raceway, and instrumentalities adapted to impart a reciprocatory and lateral motion to said needle and needle bar, whereby said needle may be projected 40 through the eye of a button on said raceway and said button removed from said raceway while the needle is through the eye of said button.
25. In a machine for attaching a button to the upper of a boot or shoe, a raceway, a needle and needle bar, a rocker-arm upon 45 which said needle bar is slidably mounted, mechanism adapted to rock said rocker-arm, and mechanism adapted to impart a reciprocatory motion to said needle bar and

needle, whereby said needle may be projected through the eye of a button on said raceway, and said button removed from said raceway while the needle is through the eye of said button.

26. In a machine for attaching a button to the upper of a boot or shoe, a needle-bar carrying a needle, a raceway and means to adjust one of said parts relatively to the other, whereby said needle may be brought into 75 alinement with the eyes of buttons of different sizes on said raceway.

27. In a machine for attaching a button to the upper of a boot or shoe, a raceway, a needle and needle bar, a rocker-arm upon 80 which said needle bar is slidably mounted, mechanism adapted to rock said rocker-arm, mechanism adapted to impart a reciprocatory motion to said needle bar and needle, whereby said needle may be projected 85 through the eye of a button in said raceway, and said button removed from said raceway, and means to adjust said rocker-arm, together with said needle and needle bar, relatively to said raceway, whereby said needle 90 may be brought into alinement with the eye of a button on said raceway.

28. In a machine for attaching a button to the upper of a boot or shoe, a needle and needle bar, a raceway, instrumentalities 95 adapted to impart a reciprocatory and lateral movement to said needle and needle bar, and adjustable means adapted to increase or diminish the extent of said lateral movement and to simultaneously adjust said raceway, 100 whereby said needle will remain, after said adjustment, in alinement with the eye of a button on said raceway.

29. In a machine for attaching a button to the upper of a boot or shoe, a needle and needle bar, a raceway, instrumentalities adapted to impart a reciprocatory and lateral movement to said needle and needle bar, means to adjust said needle and needle bar laterally thereof relatively to said raceway, 110 whereby said needle may be brought into alinement with the eye of a button in said raceway, and other adjusting means adapted to increase or diminish the extent of said lateral movement and to simultaneously adjust said raceway, whereby said needle will remain after said last named adjustment in alinement with the eye of a button on said raceway.

30. In a machine for sewing buttons to 120 the upper of a boot or shoe, a work-support provided with a slot extending longitudinally thereof and a guide-way on said work-support adapted to guide a button and extending parallel with and adjacent to said 125 slot, and a spring-pressed button holder pivoted to said work-support and having a slot therein into which the head of a button located in said guide-way is adapted to project; in combination with an eye-pointed 130

needle, mechanism adapted to impart a reciprocatory and lateral movement to said needle, whereby said needle may be passed through said upper and the eye of said button, and said upper and button fed along said work-support, with the head of said button located in said guide-way and with said needle through the eye of said button.

31. In a machine for sewing buttons to the upper of a boot or shoe, a work-support provided with a slot extending longitudinally thereof, a guide-way on said work-support adapted to guide a button and extending parallel with and adjacent to said slot, 15 a spring-pressed button holder pivoted to said work-support and having a slot therein into which the head of a button located in said guide-way is adapted to project, and a button ejector consisting of a slide guided in 20 ways on said work-support extending transversely of the slot therein and adapted to engage said button head and move the same out of said guide-way and button holder slot.

32. In a machine for sewing buttons to the upper of a boot or shoe, a work-support provided with a slot extending longitudinally thereof, a guide-way on said work-support adapted to guide a button and extending parallel with and adjacent to said slot, 25 a spring-pressed button holder pivoted to said work-support and having a slot therein, into which the head of a button located in said guide-way is adapted to project, and a button ejector consisting of a slide guided in 30 ways on said work-support extending transversely of the slot therein and adapted to engage said button head, the forward end of said slide being beveled, whereby said button may be removed from said guide-way 35 and from beneath said button holder and simultaneously rocked until the eye thereof shall be moved from a horizontal to a vertical position.

33. In a machine for sewing shank-eyed buttons to the upper of a boot or shoe, a raceway, an eye pointed needle, mechanism adapted to impart a reciprocatory motion to said needle through said upper and the eye of said button, mechanism adapted to impart 45 a lateral motion to said needle while the same is in the eye of said button, mechanism adapted to substantially impart a motion to said raceway in relation to said needle, a looper, and mechanism adapted to move said 50 looper to take a loop of thread from said needle.

34. In a machine for sewing shank-eyed buttons to the upper of a boot or shoe, a raceway, an eye pointed needle, mechanism adapted to impart 55 a reciprocatory motion to said needle through said upper and the eye of said button, mechanism adapted to impart a lateral motion to said needle while the same is in the eye of said button, mechanism adapted to subsequently impart a motion to 60

said raceway in relation to said needle, a looper having a hook at its free end, and mechanism adapted to rock said looper to take a loop of thread from said needle and to impart to said looper a lateral movement, 70 whereby said loop may be spread in the path of movement of said needle in its second upward movement.

35. In a machine for sewing buttons to the upper of a boot or shoe, a raceway, an eye pointed needle, mechanism adapted to impart a reciprocatory motion to said needle, through said upper and the eye of said button, mechanism adapted to impart a lateral motion to said needle while the same 75 is in the eye of said button, mechanism adapted to subsequently impart a motion to said raceway in relation to said needle, a primary looper having a hook at its free end, mechanism adapted to rock said primary looper to take a loop of thread from 80 said needle, a secondary looper having a hook at its free end, and mechanism adapted to move said secondary looper to take another loop of thread from 85 said needle. 90

36. In a machine for sewing buttons to the upper of a boot or shoe, a raceway, a needle, mechanism adapted to impart a reciprocatory motion to said needle, mechanism adapted to impart a lateral motion to said 95 needle, mechanism adapted to impart a motion to said raceway in relation to said needle, a primary looper having a hook at its free end mechanism adapted to rock said primary looper to take a loop of thread from 100 said needle, an independent secondary looper having a hook at its free end, mechanism adapted to move said secondary looper to take another loop of thread from 105 said needle, and mechanism to impart a lateral motion to said primary looper.

37. In a machine for sewing buttons to the upper of a boot or shoe, a raceway, a needle, mechanism adapted to impart a reciprocatory motion to said needle, mechanism adapted to impart a lateral motion to said 110 needle, mechanism adapted to impart a motion to said raceway in relation to said needle, a primary looper having a hook at its free end, mechanism adapted to rock said 115 primary looper to take a loop of thread from said needle, an independent secondary looper having a hook at its free end, and mechanism adapted to move said secondary looper to take another loop of thread from 120 said needle, the hooks on said loopers extending, respectively, in opposite directions.

In testimony whereof I have hereunto set my hand in presence of two subscribing witnesses.

JOSEPH MATHISON.
